UNITED STATES PATENT OFFICE.

ARNOLD NEUENSCHWANDER, OF LOUISVILLE, KENTUCKY.

STEAM-GENERATOR.

No. 863,552.

Specification of Letters Patent.

Patented Aug. 13, 1907.

Application filed May 4, 1906. Serial No. 315,209.

To all whom it may concern:

Be it known that ARNOLD NEUENSCHWANDER, a citizen of United States of America, residing at Louisville, in the county of Jefferson and State of Kentucky, 5 has invented certain new and useful Improvements in Rapid Steam-Generators; and he does hereby declare the following to be a full, clear, and exact description of the invention, such as will enable others skilled in the art to which it appertains to make and 10 use the same.

This invention relates to steam generators and has for an object to provide a generator embodying improved means for rapidly generating steam from a given quantity of water.

15 A further object of the invention is to provide a steam generator primarily adapted for use in fire engines and similar structures, and embodying improved means for presenting a thin film of water to the direct action of the heat.

20 A further object of the invention is to provide means whereby a column of water within the steam generator is subjected to heat both internally and externally.

With these and other objects in view, the invention comprises certain novel constructions, combinations 25 and arrangements of parts, as will be hereinafter fully described and claimed.

In the accompanying drawings:—Figure 1 is a view in vertical section of a boiler embodying the present invention, showing the steam generating tubes in side 30 elevation. Fig. 2 is a top plan view of the steam generating tubes with the top of the boiler and steam dome removed. Fig. 3 is an inverted plan view of the steam generating tubes and their connections with the fire pot and ash pit removed. Fig. 4 is a detail view in side 35 elevation partly broken away of one set of manifold tubes arranged in accordance with the present invention.

Like characters of reference designate corresponding parts throughout the several views.

40 The present invention is adapted for association with boilers of any usual and approved form shown herein diagrammatically, as an upright boiler with an outer shell 10 and a spaced inner shell 11 forming an interval between the shell and sleeve for the receipt and accommodation of a small quantity of water and with the usual space at the top of to act as a steam dome. Within the sleeve 11 are mounted a plurality of manifold tubes embodying a pair of outer tubes 12 arranged in parallelism adjacent each other and having their 45 opposite ends secured in any usual and approved manner in the adjacent sides of headers 13 and 14 at the top and bottom respectively. The headers 13 and 14 are constructed hollow, whereby chambers 15 and 16 are respectively formed in the said headers, and the 50 tubes 12 are connected with said headers in such man-

ner that the extremities of the said tubes are in communication with the said chambers 15 and 16. The headers 13 and 14 are also provided with openings at their opposite sides smaller than and concentric with the tubes 12. Through the registering openings in the 60 opposite sides of the headers 13 and 14 the tube 17 is inserted, provided at its lower end with screw threads 18, whereby the lower surface of the lower header is engaged; and the upper end of the tube 17 is expanded as at 19 in the usual manner to form a water-tight joint 65 with the upper surface of the upper header. From Fig. 4 it will be obvious that the outer tubes 12 form communication between the chambers 15 and 16 and that the interior tubes 17 extend longitudinally through the said tubes 12 and axially thereof, and are 70 open at their opposite ends externally of the headers. The headers 13 and 14 are provided centrally with nipples 20 and 21, respectively, whereby the several manifold units, as shown in Fig. 4, are connected together by any approved means, as by the pipes 22 at 75 the top and pipes 23 at the bottom, similar pipes 24 and 25 being provided for connecting the said associated manifold units with the inner sleeve of the boiler.

The manifold units, as shown in Fig. 4, may be severally connected together in any approved manner, 80 the manner of connecting shown in Figs. 2 and 3 being but diagrammatical or conventional and providing a simple means whereby the said units may be arranged in parallelism longitudinally within the sleeve of the boiler. The pipes 24 extending through the sleeve of 85 the boiler are preferably extended adjacent to the inner surface of the outer shell and are divided longitudinally as at 26, whereby a half sleeve is provided curved from the top of the extending end to direct the steam issuing from the said pipes to a proper distribution 90 about the steam dome.

What I claim is:—

In a steam generator, the combination of a boiler formed with a fluid containing space, a plurality of clusters of water tubes arranged within the boiler, an independent 95 header at each end of each of the clusters of water tubes, each of said headers being provided upon one side with openings to receive the ends of the water tubes which open internally of the headers, and upon the opposite sides with openings smaller than and concentric with the before mentioned water tube receiving openings, flues passing through the water tubes and having their ends inserted in the before mentioned openings upon the opposite sides of the headers, a nipple carried by each header, and fluid conductors connected to the nipples and establishing 100 communication between the headers and the fluid containing space in the boiler.

In testimony whereof I affix my signature in presence of two witnesses.

ARNOLD NEUENSCHWANDER.
